FISH LURE

John K. Russell, North Hollywood, Calif.

Application March 12, 1949, Serial No. 1,377

Term of patent 14 years

(Cl. D31—4)

To all whom it may concern:

Be it known that I, John K. Russell, a citizen of the United States, residing at North Hollywood, in the county of Los Angeles and State of California, have invented a new, original, and ornamental Design for a Fish Lure, of which the following is a specification, reference being had to the accompanying drawing, forming part thereof.

Fig. 1 is a side elevational view of a fish lure, showing my new design;

Fig. 2 is an elevational view of the other side of the lure;

Fig. 3 is a top plan view of the lure;

Fig. 4 is a bottom plan view;

Fig. 5 is a front end elevational view; and
Fig. 6 is a rear end elevational view of the lure.

I claim:

The ornamental design for a fish lure, as shown.
JOHN K. RUSSELL.
